UNITED STATES PATENT OFFICE.

JOHN L. ODELL, OF DELTA, OHIO.

OIL-BURNER FOR HEATING PURPOSES.

SPECIFICATION forming part of Letters Patent No. 392,219, dated November 6, 1888.

Application filed February 15, 1888. Serial No. 264,068. (No model.)

To all whom it may concern:

Be it known that I, JOHN L. ODELL, a citizen of the United States, residing at Delta, in the county of Fulton and State of Ohio, have 5 invented a new and useful Improvement in Oil-Burners for Heating Purposes, of which the following is a specification.

My invention relates to an improvement in crude-oil burners; and it consists in the peculiar construction and combination of devices that will be more particularly set forth hereinafter, and particularly pointed out in the claims.

In the accompanying drawings, Figure 1 is 15 a vertical central sectional view of a crude-oil burner embodying my improvement. Fig. 2 is a top plan view, partly in section.

A represents the base of the burner, which is circular in form, is provided at its perimeter 20 with an outwardly flared flange, B, has an enlarged central opening, C, and a flange, D, arranged concentric with and at a slight distance from said opening. A flange, E, or shoulder is thus formed between the opening C and 25 flange D.

F represents a hollow cone which is truncated on its upper end, and is provided with a depending central sleeve, G, the lower end of which is fitted within the flange D and bears 30 upon the shoulder E. The base of the cone F is supported on the base-plate A.

I represents a series of ears which are formed integrally with and project radially from the outer side of the cone, at the upper end thereof, 35 said ears being arranged equidistant apart.

L represents a smaller truncated cone, which is hollow, as shown, has its base supported on the ears I of cone F, and thereby raised above the top of said cone F, and said cone L is provided with a depending central hollow cylindrical sleeve, M, which is less in length than the depth of said cone L. Said cone L is further provided on its outer side, at its upper end, with a series of radial ears, N, which are 45 equidistant apart.

O represents a fountain or nozzle which is provided with an annular concavo-convex perimeter or lip, P. The said fountain or nozzle is supported on the ears N, as shown, and 50 is arranged at a suitable distance above the center of the cone L.

R represents an oil-inlet pipe which com-

municates with a suitable reservoir (not shown) through the center of the opening C and up through the centers of the sleeves G and M of 55 the cones. The upper end of this pipe is screwed to and communicates with the center of the base of the fountain, and said pipe is thereby adapted to supply the said fountain with oil.

S represents a conical cover which is truncated, as shown, is hollow, and has its upper side closed and its lower side open, and is provided with a series of depending feet, T, which rest upon the base-plate A, and thereby support said conical cover on said base-plate, the said cover enveloping and concealing the cones and the fountain from sight. Open spaces U are formed at the lower edge of the conical cover between the feet T.

The operation of my invention is as follows: Initial heat is applied to the burner until the same is thoroughly heated, and the crude oil from the reservoir is admitted through the pipe R into the fountain. As the oil rises in 75 the fountain it overflows the same and descends in thin sheets from the lip P onto the heated surface of the upper cone, L, where it is converted into vapor, and that portion of the oil which is not converted into vapor on the cone 80 L drops upon the heated cone F, which completes the vaporizing process. Air is admitted freely through the opening C, the hollow sleeves in the cones, and through the spaces between the said cones, and between the upper cone 85 and the fountain to the vapor under the cover S, and said air becomes commingled with the vapor, so as to render the latter combustible. The commingled air and vapor escape through the openings U at the base of the cover S, and on being ignited burn very freely and create 90 flames of intense heat and great brilliancy. Moreover, the combustion is so perfect that no smoke or noxious fumes are emitted from the burner. The flanged base-plate A serves to 95 collect any portion of the oil which may escape being converted into vapor. A crude-oil burner thus constructed is extremely cheap and simple, is very durable, and is adapted to be used successfully for generating steam and 100 for other purposes.

Having thus described my invention, I claim—

1. The combination of the base having a

central opening, the series of separate cones supported one above the other concentric with the opening in the base, a fountain or nozzle at the upper end of the series of cones and having a depending annular concavo-convex lip, a supply-pipe leading upward through the base and the series of cones and communicating with the fountain or nozzle, and a cap resting on the base and covering the cones and to the nozzle, the said cap having open spaces in its lower edge, as set forth.

2. The combination of the base-plate having the flanges B, D and central opening, C, the cone F, arranged on the base-plate and having the depending central sleeve, G, the lower end

of which is arranged in the flange D, the cone L, arranged above cone F and having the depending central sleeve, M, the fountain or nozzle arranged above the cone L, for the purpose set forth, and the top or cover S, enveloping said fountain or nozzle and the cone, substantially as described.

In testimony that I claim the foregoing as my own I have hereto affixed my signature in presence of two witnesses.

JOHN L. ODELL.
